CHANGE MAKING AND FARE REGISTERING MACHINE

Filed April 12, 1922

2 Sheets-Sheet 2

WITNESS: *Geo. Ely,*

ATTORNEY

UNITED STATES PATENT OFFICE.

ALOIS BURIAN, OF SCHENECTADY, NEW YORK.

CHANGE-MAKING AND FARE-REGISTERING MACHINE.

Application filed April 12, 1922. Serial No. 551,946.

To all whom it may concern:

Be it known that I, ALOIS BURIAN, a citizen of United States, residing at Schenectady, in the county of Schenectady and State 5 of New York, have invented new and useful Improvements in Change-Making and Fare-Registering Machines, of which the following is a specification.

This invention relates to change making 10 and fare registering machines, and the principal object is to construct a machine with one coin intake which may receive a coin of any denomination from one cent to one dollar and which will reject the cent and will 15 subtract a fare from the larger coins, returning the correct balance of change if any change is due, and which will at the same operation automatically register the receipt of the fare.

Another object is to construct a device of 20 this kind which shall co-operate by means of electric energy.

Another object is to construct a device of 25 this nature which shall be simple of construction, consisting of few parts, easily assembled, cheap to manufacture, and highly efficient for the purpose for which it is designed.

With these and other objects in view, the 30 invention resides in certain novel construction and combination and arrangement of parts, the essential features of which are hereinafter fully described, are particularly pointed out in the appended claim, and are 35 illustrated in the accompanying drawing, in which:—

Figure 1 is a vertical sectional view of my 35 improved change making machine.

Figure 2 is a transverse sectional view.

Figure 3 is a horizontal sectional view on line 3—3 of Figure 1.

Figure 4 is a detail view showing the coin 40 ejecting mechanism.

Figure 5 is a sectional view on the line 45 5—5 of Figure 4.

Like characters of reference refer to like 50 parts in all views.

While I have described my device as 55 adapted for cars where a five-cent fare is to be collected, it will be readily seen that the device can be obviously arranged to collect any other fare desired.

Referring to the drawing in detail, 10

represents a casing which may be of any suitable shape and material for the purpose 55 and which is provided with a coin receiving slot 11 and at its bottom with a pocket 12 for returning the change. Secured diagonally in the frame 10 is a channel bar 13 the bottom of which is perforated and slit 60 at 14, 15, 16, 17, 18 and 19. The bottom portion is also inclined as clearly shown in Figure 2, so that a coin inserted through the aperture 11 and sliding down the member 13 will be forced by gravity against the wall 65 13^a. The apertures 14, 15, 16, 17, 18 and 19 correspond in size respectively, to the size of a dime, cent, nickel, quarter, half dollar and dollar. As the coin passes through one of the apertures it is received by a table or 70 chute 20 and directed toward the front of the machine. Each of the chutes 20 conducts the coins received thereby into a respective tube 21.

Each tube 21 has its lower end closed by a 75 transverse portion 22 so as to support the stack of coins. Just above the member 22 the front and rear of the tube are cut away at 23 so as to form slots which expose one or more of the coins in said tube so that they 80 may be ejected by the means now to be described.

Secured to the base of the frame 10 which is of wood or other insulating material are U-shaped supports 25 of soft iron there being one member 25 for each of the tubes 21. Each member 25 supports a solenoid coil 26 which is provided with a soft iron core 27 normally held in rearmost position by a spring 28. The front end of the core 27 90 is provided with a brass finger 29 which is guided by a member 30 into ejecting relation with the coin or coins exposed at 23. Member 30 is a guard to keep finger 29 from turning. It will be readily understood that 95 when the solenoid is energized finger 29 will be moved to effect ejecting of the said coin or coins.

A register is shown at 31, and the details 100 of this are not here described as they are immaterial to the present invention. Any suitable register may be used if provided with means whereby the closing of an electric-circuit will effect registration or counting.

The tube 21 which receives the cents is not 105

provided with a bottom plate 22, and consequently when a cent is inserted in the machine it passes through aperture 15 and drops completely through the respective tube into the pocket 12. We shall now consider the result from the insertion of each of the other kind of coins in the machine, presuming that a five cent fare is to be charged.

When a nickel is placed in the machine it 10 drops through the aperture 16 and in passing down its respective chute 20 it rides over a pair of electric contacts 32 and 33, so as to bridge them and effect the closing of the circuit through them. This circuit includes

15 a battery or source of energy 34 in line 35 and a line 36, contact 32 being directly connected with line 36. Contact 33 is connected by a line 37 with a line 38 leading to the register 31, the line 35 is connected by line 39 with the register. It will therefore be seen that when the nickel bridges the contacts 32 and 33 it will close the circuit through the register and effect the counting of the fare.

20 25 When a dime is inserted in the machine it is necessary that the register be operated and that a nickel be returned to the passenger. For this purpose when the dime enters its aperture 14 and slides down its respective

30 chute 20 it bridges a pair of contacts 40 and 41, contact 40 being directly connected with the aforementioned line 36. Contact 41 is connected by a line 42 with the coil 26 of the solenoid and arranged in ejecting relation to the tube 21 containing the nickels, said coil being connected at 43 with the aforementioned line 35. Line 38 of the register is provided with a contact 44 and line 36 is provided with a contact 45. The

35 cores 27 of the nickel, dime, quarter and half-dollar ejectors are provided with respective bridges 46, the bridge 46 of the nickel ejector being adapted to connect contacts 44 and 45 when the ejector is operated.

40 45 It will therefore be seen that when a dime is placed in the machine it first effects the ejection of a nickel change, and by the operation of that ejector effects the closing of the circuit through the register for counting the fare.

50 When a quarter is inserted in the machine it drops through its respective aperture 17 and in passing down its chute 20 it bridges contacts 47 and 48, the former being directly connected to line 36. Contact 48 is connected by a line 49 with the coil 26 of the dime ejecting mechanism which is constructed of a size sufficient to expel two dimes at an operation; and the said ejector coil is connected by a line 50 with the aforementioned line 35. As the dime ejector is operated its bar or bridge 46 will connect a contact 51 on the line 38 of the register with a contact 52 on the aforementioned line 36. It

will thus be seen that when a quarter is inserted in the machine, it will first effect operation of the dimes ejector to eject two dimes and in so doing will close the circuit through the register 31 for counting the fare.

70 75 When a half-dollar is placed in the machine, it passes through the aperture 18 and in sliding down its respective chute 20 will bridge the contacts 53 and 54, the former being directly connected to the aforementioned line 36, contact 54 being connected by a line 55 to the coil 26 of the quarter ejector, said coil being connected by a line 56 with the aforementioned line 35. The bridge 46 of the quarter ejector when the latter is operated connects contact 57 on line 36 with a contact 58 on the aforesaid line 49 so that dimes ejector will thereupon be operated, and it will be remembered that when the dimes ejector is operated it automatically closes the circuit through the register. It will therefore be understood that the insertion of a fifty-cent piece effects first the ejection of a quarter, then the ejection of two dimes, and then the operation of the 85 90 register.

95 When a dollar is deposited in the machine it passes through the aperture 19 and in sliding down the respective chute 20 it bridges contacts 59 and 60, the former being directly connected with line 36 and the latter being connected at a line 61 with the coil 26 of the half-dollar ejector, said coil being connected as at 62 with the line 35. The bridge 46 of the half dollar ejector, when the latter is operated, connects a contact 63 on line 36 with a contact 64 on the aforesaid line 55.

100 This effects operation of the quarter ejector which it will be remembered will automatically effect operation of the dime ejector, the latter in turn automatically effecting operation of the register, so that a half dollar, a quarter and two dimes will be dropped into the pocket 12 and the register 110 will be operated.

115 While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claim.

120 125 What is claimed as new is:—

A change making device of the character described comprising a casing, a bridging strip secured above the base of the casing, a plurality of parallel chutes of graduated sizes arranged in said casing, a transverse member closing the lower ends of some of said chutes, a pocket underlying the lower

end of said chutes, some of said chutes having their closed ends each provided with registering slots formed in the walls thereof, U-shaped supports secured to the bridging strip and arranged in parallelism before the slotted chutes, a solenoid arranged between the arms of each U-shaped support, a finger

for each solenoid being operatively associated with the slots, and means in some of said chutes for operating the fingers as and for ¹⁰ the purpose specified.

In testimony whereof I have affixed my signature.

ALOIS BURIAN.
